CLAIM

The ornamental design for a utility table, as shown and described.

DESCRIPTION

FIG. 1 is a perspective top front right view of a utility table, showing my new design;

FIG. 2 is a perspective top rear left view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines in the drawings depict portions of the utility table that form no part of the claim.

1 Claim, 8 Drawing Sheets
